UNITED STATES PATENT OFFICE.

EDWARD P. BIDWELL, OF MONROVIA, CALIFORNIA.

WIND-SHIELD.

1,143,491.

Specification of Letters Patent. Patented June 15, 1915.

Application filed June 17, 1914. Serial No. 845,647.

To all whom it may concern:

Be it known that I, EDWARD P. BIDWELL, a citizen of the United States, residing at Monrovia, in the county of Los Angeles 5 and State of California, have invented certain new and useful Improvements in Wind-Shields, of which the following is a specification.

My invention relates to new and useful 10 improvements in wind shields, automobiles, boats and other vehicles and resides in the provision of a wind shield that is so constructed and arranged as to prevent the accumulation of moisture thereon so that the 15 operator of the vehicle may clearly see through the shield and thus avert possible accidents which often result through failure of the operator to see through a moist shield.

Another and more specific object is to 20 provide a shield that consists of a double pane mounted within a frame, said panes being spaced to provide an air space and a heating element being arranged at the bottom of the space between the panes so that 25 the panes will be heated and moisture prevented accumulating thereon.

Another object is to provide a device of 30 the character described that is of extremely simple construction, may be easily assembled and disassembled and also attached and detached to the vehicle, and which is inexpensive to manufacture.

The above and additional objects are accomplished by such means as are illustrated 35 in the accompanying drawings, described in the following specification and then more particularly pointed out as claimed.

With reference to the drawings, wherein 40 I have illustrated the preferred embodiment of my invention as it is reduced to practice, and throughout the several views of which similar reference numerals designate corresponding parts, Figure 1 is a front elevation of my wind shield, Fig. 2 is a horizontal 45 sectional view showing the heating element in the bottom of the shield, and Fig. 3 is a vertical sectional view taken through my improved wind shield.

Referring to the drawings by characters 50 of reference, the numeral 1 designates as an entirety a rectangular frame which consists of vertical end bars 2 and horizontal top and bottom bars 3 and 4. The bars 2 are provided at their longitudinal edges with 55 right angularly extending flanges 5. The

flanges 5 on one of the bars 2 are arranged in pairs so as to provide window pane receiving grooves, while the flanges 5 on the other of the bars 2 are arranged to coöperate with flanges 6 formed on the longitudinal edges of a rectangular strip 7 that are secured in any suitable manner upon the inner face of said last named side bar. The last named of the side bars 2 is removable and said removable bar is provided with 60 buttons 8 to be grasped to effect the removal. Mounted between the flanges 5 and 6 are panes of glass 9 and 10 which are spaced considerably and at their upper and lower edges engage within channel-shaped bars 11 65 and 12 which bars are carried by the bars 3 and 4 or may be formed by bending said bars 3 and 4 along their longitudinal edges into such channel shape.

The bars 3 and 4 are approximately semi-circular in cross section and mounted within the lower bar 4 is a heating element designated 13 as an entirety which comprises a suitable cylindrical core in which is mounted a wire which is given a number of turns 70 or in other words is coiled about the core. The wire is designated 14 and is connected with a suitable source of current 15 at its free end. A one point switch 16 is connected in one side of the circuit from the battery or 75 other suitable source of current 15 and is preferably arranged adjacent to the operator's seat of a vehicle, not shown, so that should the glass panes 9 and 10 become moist the operator can readily close the circuit 80 through the medium of the switch 16 and the heating element 13 will heat the panes 9 and 10 thus preventing moisture accumulating on the shield.

It is to be understood that any desirable 85 form of electrical heating element may be employed and that the lower bar may be insulated after a manner not shown, in any suitable manner so as to support or house the heating element.

In practice, I have found that the form 90 of my invention, illustrated in the drawings and referred to in the above description, as the preferred embodiment, is the most efficient and practical; yet realizing that the 95 conditions concurrent with the adoption of my device will necessarily vary, I desire to emphasize the fact that various minor changes in details of construction, proportion and arrangement of parts may be re- 100 105 110

sorted to, when required, without sacrificing any of the advantages of my invention, as set forth.

What is claimed is:—

- 5 A wind shield comprising a frame including opposed bars, pane supporting bars carried by the opposed bars, panes carried by the supporting bars and spaced from one another and a heating element carried by

the lower of the bars and disposed below 10 the lower edges of the panes.

In testimony whereof I affix my signature in presence of two witnesses.

EDWARD P. BIDWELL.
